UNITED STATES PATENT OFFICE.

STEPHEN KOSTRZEWSKI, OF NEW CANAAN, CONNECTICUT, ASSIGNOR TO ABRAHAM STOLZER, OF NEW YORK, N. Y., DOING BUSINESS UNDER THE NAME AND STYLE OF NEW ENGLAND INCANDESCENT SUPPLY COMPANY.

DESIGN FOR A CEILING LIGHTING FIXTURE.

Application filed March 16, 1926. Serial No. 16,940. Term of patent 3½ years.

To all whom it may concern:

Be it known that I, STEPHEN KOSTRZEWSKI, a citizen of Poland, and a resident of White Oak Shade, New Canaan, county of Fairfield, and State of Connecticut, have invented a new, original, and ornamental Design for a Ceiling Lighting Fixture, of which the following is a specification, reference being had to the accompanying drawing, forming a part hereof.

The drawing shows a side elevational view of the ceiling lighting fixture.

I claim:

The ornamental design for a ceiling lighting fixture substantially as shown.

STEPHEN KOSTRZEWSKI.
